UNITED STATES PATENT OFFICE.

HORACE E. FINE, OF TRENTON, NEW JERSEY.

NUMBERING DEVICE.

No. 833,377.

Specification of Letters Patent.

Patented Oct. 16, 1906.

Application filed January 13, 1906. Serial No. 295,857.

To all whom it may concern:

Be it known that I, HORACE E. FINE, a citizen of the United States, and a resident of the city of Trenton, State of New Jersey, 5 have invented certain new and useful Improvements in Numbering Devices, of which the following is a full, clear, and complete disclosure.

My invention relates to devices for displaying identification-signs, and particularly to those which are carried upon automobiles.

The object of my invention is to so construct such a device that the same may be readily inserted in or detached from the interior of any circumferential or other inclosing portion; and it consists of a resilient wire loop within which is attached a frame for holding numbers or other means of identification, the said loop having a portion there- 20 of adapted to be compressed or so reduced in area that it may be passed through an orifice and expand again into a circumferential or other like inclosure.

My invention also consists in further features of construction and manner of operation, the details of which are set forth in the following specification and accompanying drawings, in which like reference characters refer to corresponding parts.

30 In the drawings, Figure 1 is an elevation of my invention, located in the front of an automobile-lamp door, showing a part of the lens broken away. Fig. 2 is a perspective view of the same detached from the vehicle, the contracted portion being indicated in dotted lines. Fig. 3 is a rear view of the frame for holding the identification-signs and a fragmentary portion of the loop. Fig. 4 is a longitudinal section taken on lines 3 3 of Fig. 3. 40 Fig. 5 is a transverse section taken on lines 4 4 of Fig. 3.

In Fig. 1, 1 represents the bead on the front of the door of an automobile-lamp, in which the lens 2 is supported. The lens is partially 45 broken away at its upper portion, showing the outer edge of the door-flange 3 in longitudinal section 4. My sign-carrying device may be seen above the broken-away portion and also through the lens 2 in its position in 50 the door of the lamp.

Referring to Fig. 2, 5 5' show the extremities of the loop, which extend upwardly and parallel with each other until they are turned into coils 6 6'. These extremities may be 55 bent to any configuration, according to the location in which it is desired to place the de-

vice. The said portions then continue upwardly from the coils 6 6', turning toward each other until they intersect and are turned around a circle, forming a coil 7.

60

It is obvious that I may substitute for the coil 7 any other bends, the depressions of which would cause an inward yielding action of the loop.

Immediately below the coils 6 6' is fastened the frame 8. This frame is substantially rectangular and is skeleton in form, having its face portion cut out to form a rectangular orifice. The ends of this frame are extended in the form of tongues, which are 70 turned back upon themselves around the loop portions, as shown at 9 9'. Each leg of the loop where the tongues 9 9' fold around the same is bent inwardly in the form of a kink to prevent the frame from sliding up or 75 down or turning upon the wire. From the upper and lower edges of the frame also extend tongues, which are turned back upon themselves over the upper and lower edges of the identification-signs to hold the same in 80 position, as shown at 10 10'. These identification-signs may be of any peculiar character—such as letters, designs, emblems, &c.—and they may be in separate parts or all represented on one piece of metal or other material; but in the drawings I have illustrated them as numbers, each number cut out of a 85 flat metallic plate. I slide these plates into the slots formed by the turned-back portions 10 10' and fasten them in place by swaging 90 down the turned-back portions over the edges of the same before the tongues 9 9' are folded around the loop portions.

In contracting the device in order that it may enter the back of the door of the lamp I 95 pass one finger through the coils 7, which serve as a finger-hole, and my thumb under the frame. At the same time, pulling down on the coils 7, I draw the loop into the position shown by the dotted lines in Fig. 2. In this 100 position I may pass it through the opening in the rear of the lamp-door up against the lens, where I permit the loop to expand again until it is resisted by contact with the inner peripheral portion of the lamp-bead. In this 105 position the two extremities or feet 5 5' rest in the bottom part of the lamp-door. During this operation the frame is prevented from sliding upwardly on the loop by means of the kinks and the inwardly-projecting coil 110 6 6'. The loop is made out of a single piece of resilient metallic wire, and by virtue of the

location of the two side coils and upper middle coil one can shorten both the length and width of the intermediate, or that portion above the frame, when the coils 7 are drawn downwardly. I may utilize any character of identification devices, such as a card made of paper or any other material having a number or sign represented thereon.

I have described my device as applied to 10 an automobile-lamp; but the same may be used upon other lamps or in any location where a removable identification device is desired, and although throughout this specification I have used various terms—such as 15 "signs," "frames," "loops," "coils," &c.,—I do not wish to be limited to the exact construction of the same as illustrated and described, but reserve the right to utilize any of the well-known equivalents thereof, provided 20 that they are within the scope of my invention and as pointed out in the appended claims.

What I claim, and desire to secure by Letters Patent, is—

- 25 1. A support for identification-signs, consisting of an inwardly-yielding loop and a frame for displaying signs fastened within said loop.
- 30 2. A support for identification-signs, consisting of an inwardly-yielding loop and a substantially rectangular frame for displaying said signs, having two of its opposite edges bent back upon themselves to fasten said signs in position.
- 35 3. A support for identification-signs, consisting of an inwardly-yielding loop and a substantially rectangular frame for displaying said signs, having two of its opposite edges bent around said loop to fasten said frame in position.
- 40 4. A support for identification-signs, consisting of a loop having two parallel portions adjacent to their extremities, the said parallel portions terminating in a resilient intermediate portion having inwardly-projecting

coils, the said intermediate portion being adapted to yield inwardly, and a frame for displaying said signs fastened within said loop.

5. In a support for identification-signs, the combination of a resilient and inwardly-yielding loop, with a substantially rectangular frame for displaying said signs, the said frame being fastened to and included within said loop. 50

6. In a support for identification-signs, the combination of a resilient and inwardly-yielding loop, with a frame having tongues on two of its sides, adapted to be bent back upon themselves to fasten said signs in position. 55

7. In a support for identification-signs, the combination of a resilient and inwardly-yielding loop, with a frame having tongues projecting from two opposite edges thereof, 60 the said tongues being folded around portions of said loop near its extremities.

8. In a support for identification-signs, the combination of a resilient and inwardly-yielding loop, with a frame having projecting 70 tongues on opposite sides thereof, the said tongues being bent around parallel portions of said loop.

9. In a support for identification-signs, the combination of a loop having parallel extremities and an inwardly-extending coil intermediate said extremities, with a frame for displaying said signs fastened to said parallel extremities. 75

10. In a support for identification-signs, 80 the combination of a loop having parallel extremities, a coil intermediate said extremities and a further coil between each of said parallel portions and said intermediate coil.

In witness whereof I have hereunto set my hand this 12th day of January, A. D. 1906.

HORACE E. FINE.
